BUILDING CONSTRUCTION.

1,242,609.

Specification of Letters Patent.

Patented Oct. 9, 1917.

Application filed June 20, 1916. Serial No. 104,682.

To all whom it may concern:

Be it known that we, JOHN SCHUMACHER and JOSEPH E. SCHUMACHER, both citizens of the United States, residing at Los Angeles, in the county of Los Angeles and State of California, have jointly invented new and useful Improvements in Building Constructions, of which the following is a specification.

10 This invention relates to composite lathing and methods of applying the same, and more particularly relates to composite lathing including both plaster-board and metallic elements which are suitably connected together for associated use, means being provided for affixing or applying the same to the building structure and likewise for holding the plaster-board element and the metallic element together. To such 20 composite lath plaster may be applied in the usual manner, becoming firmly inter-engaged with the metallic lathing element and spread over the same and the plaster-board lathing element, and thus providing the 25 finished plaster wall surface. In employing such a composite lathing the plaster-board element may be directly affixed to the building structure or may be held to the building structure by the means which hold together 30 the plaster-board element and the metallic element in assemblage. The peculiar method of use assembling these elements in accordance with the invention, and the particular and peculiar means entering into 35 the invention for so assembling these elements together and for applying the lathing to the building structure, renders it possible to operate in applying the lathing from a single side or surface thereof, 40 namely, the surface to which ultimately and finally the plaster is applied to produce the plaster finish. Thus the composite lathing may be rapidly and effectively installed and finished, and such work may be done progressively by a single operator without the assistance of a helper, if desired. Furthermore the composite lathing is of course of greater strength and tends to maintain its formation better than in the sole use of metallic lathing, and the building or wall thereof is by the plaster-board element rendered practically fire-proof, sound proof and weather proof, independently of and without relying upon the plaster finish 50 which is applied to the lathing, such plaster finish thus being likewise protected from

fire and weather by such backing of composite lath. The metallic element of the composite lath is also entirely embedded within the finishing plaster or plastic body, 60 acting as a bond or reinforcement for the same and producing greater inherent structural strength. Likewise, the means utilized for holding in assemblage the plaster-board element and the metallic element and holding the same, if desired, to the building structure, are all embedded in the plaster or plastic element and constitute a bond or reinforcement for the same, likewise extending through the plaster-board and, 70 where used to attach the composite lathing to the building structure, thus serve to directly unite the plastic finish or surface material, together with the other elements of the lathing with the skeleton or frame of 75 the building. Such means likewise are capable of application and use, by the peculiar and novel means and method incident to the invention, without drilling, notching or otherwise altering the structure of the 80 building frame, be it of wood or metal. This results in a saving in time as well as conserving structural strength. It will be noted that all of the parts and features of a 85 wall built up to include such composite lathing are fire-proof, and the same will remain intact even if combustible portions of the building burn, so long as the skeleton or frame of the building to which the lathing and walls are applied is capable of 90 resisting combustion.

The invention has for its objects the provision of a composite lathing and wall resultant upon the use of such lathing, and the institution of improved means for assembling and constructing and applying such features, generally in accordance with the above statements, and otherwise, and which will be superior in point of relative simplicity and inexpensiveness of construction and formation, economy in labor, inherent structural strength and durability, resistance to the elements, insulation with respect to sound and convenience and economy in application and installation, and 100 which will be generally superior in efficiency and serviceability and practicability.

With the above and other objects in view, the invention consists in the novel and useful provision, formation, combination, association, relative arrangement, inter-relation of parts and elements and features, and

method of procedure and performance, all as hereinafter described, shown in the drawing and finally pointed out in claims.

In the drawing:

5 Figure 1 is a front elevation of a fragment of a wall including a composite lathing constructed and organized in accordance with the invention, a plaster covering being applied to such lathing and being broken 10 away in part for better illustration of the lathing, such figure likewise showing means for uniting the lathing elements, and if desired, for mounting the same and the plaster upon the frame of the building with slight 15 modification;

Fig. 2 is a vertical sectional view of the same taken upon the line x^2-x^2 , Fig. 1, and looking in the direction of the appended arrows;

20 Fig. 3 is a fragmentary rear elevation of the wall structure shown in Figs. 1 and 2, looking in the direction of and at the region indicated by the arrow in Fig. 2;

Fig. 4 is a side view of means for assembling together the lathing elements as disclosed in Figs. 1 to 3 inclusive, the same being in detached position and in the relation its parts assume or present prior to application to the lathing elements; and

25 Fig. 5 is a view similar to Fig. 2 of a modified form of construction of the uniting means and modified frame construction to which the lathing and wall are applied and with which the same are connected by 30 such means.

Corresponding parts in all the figures are designated by the same reference characters.

Referring with particularity to the drawing, the improved composite lathing therein disclosed comprises a plaster-board element A, a metallic element B, and means or clips C, whereby said elements are held together in assemblage, in Figs. 1 to 4 inclusive, similar means or clips D being disclosed in Fig. 45 5, in modified form, for the same purpose and for the further purpose of holding the lathing and the plaster surface applied to the same to the building frame.

The lathing element B consists of what is 50 commercially known as metal lath being preferably of foraminous construction and consisting of perforated sheet metal which is applied to the plaster-board element A so as to be bonded within and to reinforce the plaster covering or surface E applied to 55 the plaster-board element A and said metal element B and over the same. The plaster-board element may be directly tacked or nailed or otherwise secured to the frame of 60 the building, indicated at F in Fig. 2, as for instance by screws 6; whereas in Fig. 5 the plaster-board element A and the metallic element B are shown as held together by the means D which likewise secure the said elements A and B to the building frame

a member of which is shown at G, as of channel iron construction.

The plaster-board element may first be nailed up or otherwise put in position upon the frame members F, and the metallic element B in sheets of convenient dimensions, then attached thereto by the means C; or the two elements A and B may be assembled at the factory or prior to installation of either element, the elements A and B united 70 by the means C being jointly installed as by nailing to the building framework. In either case suitable holes 7 are punched or drilled at proper intervals through the plaster-board element A, each to receive one of 75 the means C, which is preferably formed of a single length 8 of pliable metallic wire formed centrally into an elongated body loop 8^a and one end portion of which is angled as at 8^b and 8^c to produce a terminal 80 portion at 8^d to lie in a plane spaced from that of the body loop and approximately parallel therewith. The other end portion is brought into engagement with the first 85 mentioned end portion at the bend 8^b therein and prior to use ranges angularly from the plane of the body loop 8^a in a direction opposite to that in which the first named end portion is bent, producing a terminal 90 portion 8^e which may be depressed or re-turned substantially into the plane of the body loop 8^a as shown in dotted lines in 95 Fig. 4. In applying each such means C, the terminal portion 8^d is entered through the hole or opening 7 and brought to bear 100 in its extension upon the rearward surface of the element A being first passed through one of the openings in the metallic element B, to bring the body loop 8^a to bear down upon such element B. The terminal portion 105 8^e is then depressed and brought to bear upon the element B ranging in a direction the opposite from that assumed by the body loop 8^a, so that such terminal portion 8^e and such body loop assume an end-to-end 110 relation, extending materially over the element B and binding the same firmly against the element A. The said body loop and terminal portion 8^e may be subjected to pressure by pliers or any suitable implement, to 115 increase the force of the grip, whereby the elements A and B are jointly embraced between the clamping jaws 8^a and 8^e on the one hand and the clamping jaw 8^d on the other hand.

In the form of construction shown in Fig. 5 the means D in each instance is constructed in accordance with the construction and formation of the means C in the other figures, with the modification that the length 120 of material of the wire body 8 between the bends 8^b and 8^c is increased so that a beam such as G may be engaged by the terminal portion 8^d in hooked engagement. In assembling the parts and elements and applying 130

the composite lathing to the frame of the building, including the beam G, the terminal portion 8^a is first inserted through the respective hole or opening 7, after having 5 been passed through the mesh of the element B with the terminal portion 8^a ranging parallel with the beam G. When such terminal portion has been brought to the rear extremity of such beam G, the entire 10 device D is given a one-quarter turn, bringing such terminal portion 8^a into hooked engagement with the beam G, whereupon the terminal portion 8^a is brought to bear upon the element B in the same manner as 15 in the other figures, the lathing elements being firmly bound together and jointly applied and held to the frame of the building. In Fig. 5 one of the means D is shown in process of insertion in a position for engagement 20 with a beam G. This is shown in the upper portion of such figure. In the lower portion of such figure the means D is shown as in engagement with the beam and as brought into final clamping position of its 25 parts to hold the elements together and to the beam. It is to be understood that further means C may, and preferably are, provided to hold the elements A and B together at points falling between the zones of the 30 lathing where the same are held to the beam G.

The plaster or plastic covering E is spread or massed completely over the element B and the face of the element A behind such 35 element B, as shown in part in Figs. 1 and 5, the element B being firmly embedded within the plastic element E and reinforcing and bonding the same, adding to the inherent strength of the plastic covering, and 40 likewise intimately uniting and binding such plastic covering with and to the element A and resultantly to the frame of the building.

It will be apparent that the wall so constructed, namely, including the two elements 45 A and B, and the plastic covering applied to the same, is of high superiority with re-

spect to inherent structural strength, resistance to the elements, and as a sound insulating structure; and that it may readily be assembled as to its various parts and installed in position with a minimum of labor and economy of time, all operations being performed at and from one face or side of such wall and the various parts thereof as it is 55 formed.

When such advantages and elements of superiority are considered, the extreme inexpensiveness of the composition lathing and wall resultant upon its use becomes ap- 60 parent.

It is manifest that many variations and modifications and substitutions may be made with respect to the showing of the drawing and the disclosure of the foregoing description and statement, in adapting the same to varying conditions of use and kinds of service, without departing from the spirit of the invention. 65

Having thus disclosed our invention, we 70 claim and desire to secure by Letters Patent:

In fastening means for securing lath and plaster board, a clip having initially widely angled parts, one of which is adapted to be passed through plaster board and metal lath 75 and into engagement with one thereof, and the other of which parts is adapted to be brought to bear upon the other of said plaster board and metal lath after such introduction; said clip being provided with a 80 body portion from which such parts range and which likewise is adapted to bear upon one of said elements; said clip being formed of a single length of pliable wire formed into a loop to constitute said body part, and 85 providing at its ends said other parts.

In testimony whereof, we have signed our names to this specification in the presence of two subscribing witnesses.

JOHN SCHUMACHER.

JOSEPH E. SCHUMACHER.
